ROAD BRUSH

Ora W. Bentley and Charles L. Stover, Seattle, Wash., assignors to Ora W. Bentley, doing business as Northwest Toro Co., Seattle, Wash.

Application August 12, 1940, Serial No. 352,286

11 Claims. (Cl. 15—82)

This invention relates to a road brush, incorporating a rotary broom of large size and considerable weight, having many uses, such as brushing loose dirt upon a finished hard-surfaced roadway, distributing the top surface of a gravel roadway, or cleaning the surface of a hole, which is to be patched, in an oil or asphalt road, and snow removal from streets and highways.

It is desirable to arrange such brooms sometimes to sweep straight ahead, sometimes to sweep to the right, and sometimes to sweep to the left, instead of their being fixed more or less in one position, and the provision of a broom and support to this end is one of the objects of the invention.

With such an arrangement it is necessary that the broom be so mounted that it may tilt sidewise, whatever its transversely swung position, to the end that it may follow closely and conform to the irregularities of surface contour and of slope of the roadway. It is also necessary that it be so mounted that the degree of its pressure upon the roadway in any position may be adjusted at will, and in such a way that in movement from one point of use to another the broom may be entirely lifted clear of the roadway.

Thus the desired movements of the broom are in effect about three axes—a sidewise tilting about a substantially horizontal longitudinal axis, a transverse swinging about an upright, usually centrally disposed axis, and a bodily lifting movement about a transverse horizontal axis, and it is an object so to mount the broom that it may partake of any of these movements independently of or without regard to the broom's position about another axis, and notwithstanding its weight and the necessity of making it sufficiently rugged for long, trouble-free use.

It is, of course, desirable to fix its transversely swung position to whatever angle is desired, and so to fix it in this transversely swung position that its freedom of sidewise tilting and of bodily lifting are not affected.

Likewise it is desirable to mount such a brush, or to provide means whereby it may be mounted, upon a road vehicle such as is commonly called a tractor or utility vehicle, in such manner that the broom may be power driven, preferably by a motor carried upon the frame whereon the broom is journaled, and which partakes of the movement of the broom, and which yet can be controlled from the driver's seat on the vehicle. Likewise it is desirable that it be so mounted upon the vehicle that it may be readily applied thereto and detached therefrom when the vehicle

is to be used for other purposes. These are among the objects of this invention.

Among other more specific objects are the provision of suitable mechanism to simply and conveniently accomplish the above ends, and in particular the provision of mechanism which will properly and resiliently support the broom and take at least part of its weight from the vehicle, yet still so arranged as to permit the required movements of the broom without interference.

It is also an essential object to construct the brush ruggedly, for it must withstand all sorts of abuse and rough usage, in practical operation.

In the drawings the invention, embodied in a typical form, has been shown as mounted upon a tractor or utility vehicle, generally designated a road vehicle, but it will be understood that the form of the vehicle itself is not part of the invention, nor, except in a general sense, is the particular manner in which the brush is mounted upon the vehicle.

Figure 1 is a side elevation of the road vehicle and road broom in assembled and operative relation, with the brush moved about the axis of transverse swinging to brush straight ahead.

Figure 2 is a plan view of the same combination, showing the capability of adjustment by transverse swinging of the broom.

Figure 3 is a front elevation, with parts broken away, of the same combination.

Figures 4 and 5 are front elevations, showing the manner in which the broom tilts sideways following the contour of the road.

The road vehicle, generally designated 9, includes a chassis 90, road wheels 91, a hood 92 enclosing the engine, the driver's seat 93, and suitable controls 94. The details of the vehicle, as has been indicated, are of no importance in the present invention. Power for rotating the broom is derived from a separate motor, as will shortly appear.

For convenience of mounting the brush upon such a vehicle and dismounting it therefrom we provide an adaptor frame including the longitudinals 86, which coincide with the chassis 90 and are secured thereto by convenient means such as the bolts 81. The two longitudinals 86 are joined by a front plate 82 which projects in front of and somewhat below the chassis, in relation to the vehicle illustrated. Upon this plate 82 is mounted the main support of the broom 1 from the vehicle, this main support consisting of a universal joint 8. Insofar as the principle of operation is concerned, it may be considered that the supporting structure, down to the universal

joint 8, is part of the vehicle itself, inasmuch as the separate supporting frame is merely for convenience of attachment to and detachment from the vehicle 9.

The broom 1 is journaled at 11 in a rugged journal frame 10, having a rearward extension 12, whereon is carried a part of the universal joint 8. The universal joint is of any suitable type, but should be so arranged that it affords movement of the broom 1 and of the frame 10 about at least two axes, and preferably about three axes, each of which is at right angles to the other two. The first such axis is a centrally disposed horizontal longitudinal axis, represented at I, which permits sidewise tilting of the broom 1 and frame 10. The second axis is an upright axis, represented at II, which permits sidewise swinging of the broom and adjustment of the angle of its axis of rotation with respect to the longitudinal axis of the vehicle 1 and the direction of movement. The third axis, represented at III, is a transverse, substantially horizontal axis, and this permits bodily lifting of the broom clear of the roadway. If each of these three axes intersects in the universal joint, as is preferred but not strictly essential, movement of the broom about any one of these axes, or about any two of them, will not affect nor be affected by its position with respect to the other axis or axes.

The broom is preferably rotated by power drive mechanism which includes the motor 1 carried upon the journal frame 10, upon brackets 10, the drive chain 71 running over suitable sprockets on the engine shaft and upon the brush shaft, respectively, as seen in Figure 1, and a clutch 75. The drive is thus extremely simple and rugged.

This assembly, including the broom, frame, and hood, is rather heavy. It is supported mainly by the universal joint 8, which has no rigidity, yet the heavy assembly may not be permitted to support its entire weight upon the bristles of the broom bearing upon the roadway, for it is necessary that the bristles be free to brush fairly lightly over the roadway, for the best effect. Moreover, it is necessary to lift the broom bodily clear of the roadway when transporting it from place to place. Further supporting and movement-limiting or governing means must be provided, and these must react primarily from the adapter frame 80, 82.

Accordingly, to support the brush we provide an auxiliary support, in addition to the universal joint at 8, the auxiliary support including a leg or A-frame 2 pivoted upon the frame members 81 upon a transverse axis at 20, and carrying, adjacent its upper end, well above the universal joint at 8, a sheave 21. This sheave is supported generally in the axis II. A bridle formed by the cable 22, passing over the sheave and secured at 23 to the opposite ends of the frame 10, will support such proportion of the weight of the broom as is desired when the leg 2 is suitably held upright, and the bridle permits sidewise tilting of the broom, as roadway conditions dictate, thus permitting the broom to bear with the same force upon the roadway, throughout its length, regardless of inequalities of surface. A spring 24, connected between the leg 2 and a bracket 84 upon each of the frame members 80, takes a part of the weight of the broom, and the remainder, a sufficiently small proportion to be handled by the operator, is taken by a tension member such as the cable or rod 25 extending from the leg 2 to a control lever 26 adjacent the operator's seat 93.

The operating lever 26 is provided with a holding dog 27 cooperating with a quadrant 28 secured to the chassis 90, which is preferably notched. The effective length of the rod or cable 25, and therefore the proportion of the weight of the broom which is permitted to rest upon the roadway, is adjusted initially, and from time to time as the broom wears away, by means such as the turn-buckle 28. The adjustment during operation is by means of the lever 26 and quadrant 28.

The broom is transversely swingable about the vertical axis II, but it must be held in its position of adjustment, whether that be straight ahead or swung to the right or to the left. To this end we provide chains or similar elements, indicated at 3, extending from eyes 30 adjacent the ends of the frame to hooks or similar securing means 85 carried upon the longitudinals 80 of the adapter frame. By increasing the effective length of one chain and taking up on the other, the broom may be swung about the axis II and held in any transversely swung adjusted position. The effective length of the chains may be adjusted by turnbuckles 33. Since the sheave 21 is included in the axis II about which this transverse swinging is accomplished, it will be evident that the transverse swinging of the broom from one position to another does not in any way affect the support of the broom, nor the proportion of its weight which is permitted to rest upon the roadway, nor the sidewise tilting adjustment of the broom.

The broom is tiltable sidewise about the axis I, as has already been pointed out. In so tilting the bridle 21 is in effect shortened at one side and correspondingly lengthened at the opposite side, the cable 22 running back and forth to a limited extent through the sheave 21 as the broom tilts, and the bridle, composed of the cable 22, always supports the main weight of the broom. However, to further support the broom to tend to return it, after tilting, always to its neutral position, substantially horizontal, we provide an arm 40, which is pivoted between its ends at 41 in the axis II, and extension springs 4 which extend between the ends of the arm 40 and the corresponding ends of the frame 10. Since the pivot 41 of the arm 40 lies in the axis II about which the transverse swinging of the broom is accomplished, the arm follows the transverse swinging of the broom, but not its sidewise tilting, and the support of the broom and the equalization of its sidewise tilting, due to the springs 4, is not affected by any sidewise swinging of the broom.

When it is desired to lift the broom clear of the ground, or to adjust its position bodily vertically, this may be accomplished without material disturbance of any other adjustment or support, by merely pulling back the control handle 26, from the driver's seat. This acts through the cable or rod 25, the leg 2, and the bridle 22 to lift the forward portion of the frame 10 about the axis III. The springs 4 are thereby relaxed somewhat, but still have sufficient force to maintain the broom substantially horizontal. The chains 3 slack off somewhat, but not sufficiently to permit any undue swinging of the broom from side to side. The springs 24 relax somewhat, but may be so arranged that they still bear a material part of the weight of the broom.

The motor 1 is preferably mounted upon the frame 10 and partakes of all the movements of the frame and of the broom. In this way a simple drive arrangement of the broom is afforded. The

motor 1 has a clutch 15 engageable to drive the broom, but no material adjustment of the motor's speed is required, and therefore no throttle control is provided for the operator, but it is desirable that the operator be enabled, from his seat 93, to stop the motor 1, if need be. To this end an ignition control switch 13 is provided on the vehicle 9 adjacent the driver's seat 93, and a wire 14 extends thence to the motor 1.

Should it be desired to dismount the brush for the purpose of using the vehicle 9 for other purposes temporarily (for example, to use a grass cutter mounted along one side), it is only necessary to remove the four bolts 81, one on each side of the vehicle 9, and to disconnect the rod 24 from the control handle 26. The handle 26 is not in the way, although it, too, can readily be removed, or by rearward extension of a frame member 80, the handle 26 might be mounted upon the demountable adapter frame. With the above disconnections made the entire brush may be removed from the vehicle as a complete unit. It can be restored with equal facility, without disturbance of the operative relationship of its parts.

It is to be particularly noted that the broom may be swung transversely, as shown in Figure 2, either to right or to left or straight ahead, and in any position it has full freedom to tilt sidewise; as the contour of the roadway may require. Likewise in any sidewise tilted position or in any transversely swung position of the broom it may be lifted clear of the roadway, or its pressure upon the roadway may be conveniently adjusted.

The brush has been shown as mounted at the front of the vehicle 9, as would be customary; but it might, if preferred, be mounted at the rear thereof. Likewise while it would normally brush forwardly, it may be so arranged as to brush to the rear, or in the opposite direction to that shown.

What we claim as our invention is:

1. In combination with a road vehicle, a transversely extending road broom, a single universal joint between the vehicle and the broom, centrally disposed and arranged to afford pivotal sidewise tilting movement of the broom, transverse swinging thereof, and its bodily vertical movement about a transverse horizontal axis, and an auxiliary support pivoted upon the vehicle upon a transverse horizontal axis, spaced from the broom's corresponding axis, said auxiliary support being disposed above the broom and in line with the axis of transverse swinging, tension means extending thence to the opposite ends of the frame, and mutually and oppositely extensible and contractible in effective length to permit the sidewise pivotal tilting, and means to shift said auxiliary support rearwardly about its transverse axis, thereby to move the broom bodily, through the tension means, about its own transverse horizontal axis, clear of the roadway.

2. In combination with a road vehicle, a transversely extending road broom, a universal mounting between the vehicle and the broom, centrally disposed and arranged to afford sidewise tilting movement of the broom, and transverse swinging thereof, an arm pivoted between its ends above and substantially in line with the axis of transverse swinging, and means extending between the opposite ends of said arm and the corresponding ends of the broom, tending to support the broom in level position, but yieldable to permit its tilting, and swingable with the broom as it swings transversely.

3. In combination with a road vehicle, a transversely extending road broom, a universal mounting, a frame whereon the brush is journaled, a universal mounting between the vehicle and the broom, centrally disposed and arranged to afford pivotal movement of the broom about three distinct axes, namely, for sidewise tilting movement of the broom, for transverse swinging thereof, and for bodily up and down movement thereof, an arm pivoted between its ends above and substantially in line with the axis of transverse swinging, means extending between the opposite ends of said arm and the corresponding ends of the broom, tending to support the broom in level position, but yieldable to permit its tilting, and swingable with the broom as it swings transversely, an auxiliary support carried by the vehicle and located above said arm and in the axis of transverse swinging, tension means extending thence to the opposite ends of the broom, and means to shift said auxiliary support rearwardly, thereby to tilt the broom and to lift it bodily clear of the roadway.
4. In combination with a road vehicle, a transversely extending road broom, a universally tiltable support between the vehicle and the broom, centrally disposed and arranged to afford independent pivotal movement of the broom about three distinct axes which intersect in a common point, namely, for bodily up and down movement of the broom, for sidewise tilting thereof, and for transverse swinging thereof, a leg pivoted upon the vehicle upon a transverse axis, a sheave carried by its swinging end, in line with the axis of the broom's transverse swinging and above said common point, a cable passing over said sheave and thence to the opposite ends of the broom, whereby to support the broom for sidewise tilting in any transversely swung position, and means reacting from the vehicle to swing the leg rearwardly, and, through said cable, to swing the broom upwardly, in any adjusted position of the broom, clear of the roadway.
5. In combination with a road vehicle, a transversely extending road broom, a universal mounting between the vehicle and the broom disposed and arranged to afford sidewise tilting movement of the broom, transverse swinging thereof, and bodily up and down movement thereof, an arm pivoted between its ends above and substantially in line with the axis of transverse swinging, extension springs between the opposite ends of said arm and the corresponding ends of the broom, tending to support the broom in level position, and swingable with the broom, means to adjust and fix the transversely swung position of the broom, a leg pivoted upon a transverse axis upon the vehicle, a tension member extending from said leg to the broom, as a support for the broom, and means to tilt said leg to lift the broom bodily clear of the roadway.
6. In combination with a road vehicle, a rigid supporting frame, a single, substantially universal pivotal support for the frame from the vehicle, arranged to permit bodily movement of the frame about three distinct axes, namely, for sidewise tilting about a first, longitudinal horizontal axis, for transverse swinging about a second, upright axis, and for bodily up and down movement about a third, transverse horizontal axis, a road broom rigidly supported in said frame, for adjustment relative to the roadway solely by means of adjustment of the frame relative to the vehicle, means reacting between the vehicle and

the frame to fix the position of the broom about each of the second and third axes, an arm pivotally mounted upon the vehicle for swinging about the second axis, and spring means interposed between the frame and said arm, tending to maintain the position of the frame and broom about the first axis, in all positions around the second axis, but yieldable to permit their bodily sidewise tilting about the first axis.

7. In combination with a road vehicle, a transversely extending road broom, a single pivot means supporting the broom from the vehicle for bodily movement about at least two axes which intersect in a common point, namely, a first, longitudinal horizontal axis for sidewise tilting, and a second, transverse horizontal axis for raising and lowering, said pivot means being disposed behind the broom and centrally between its ends.

8. In combination with a road vehicle, a transversely extending road broom, a single pivot means supporting the broom from the vehicle for bodily movement about a first, longitudinal horizontal axis for sidewise tilting, and about a second, upright axis for transverse swinging, said pivot means being disposed behind the broom and centrally between its ends, an auxiliary support carried by the vehicle and pivoted above the broom for swinging only about the broom's second axis, and means supporting the ends of the broom from the respective ends of the auxiliary support, and yieldable for tilting of the broom bodily about its first axis.

9. In combination with a road vehicle, a road broom, a rigid frame whereon said broom is mounted, and a single universal pivot support mounting said frame upon said vehicle for swinging movements of the frame and broom about three axes intersecting in a common point,

namely, a tilting axis extending generally horizontally and generally longitudinal relative to the vehicle, an upright axis for lateral swinging to positions diagonal with respect to the longitudinal axis of the vehicle, and a horizontal axis extending transversely relative to the vehicle for movement to lowered and raised operative and inoperative positions, respectively.

- 5 10. In combination with a road vehicle, a road broom, a rigid frame whereon said broom is mounted, pivot means supporting said frame from said vehicle for sidewise tilting of the frame and broom about an axis extending generally horizontally and generally longitudinally relative to the vehicle, and resilient means reacting from the vehicle tending to restrain tilting of the frame about such axis, but yieldable to permit sidewise tilting of the frame to dispose the brush generally parallel to the road surface.
- 10 15. 11. In combination with a road vehicle, a road broom, a rigid frame whereon said broom is mounted, pivot means supporting said frame from said vehicle for sidewise tilting of the frame and broom about an axis extending generally horizontally and generally longitudinally relative to the vehicle, and also for swinging about an upright axis to positions diagonal with respect to the longitudinal axis of the vehicle, means reacting from the vehicle to fix said frame in such 20 a diagonally swung position, and means reacting from the vehicle tending to restrain tilting of the frame about the first axis in such diagonally swung position, but yieldable to permit sidewise tilting of the frame to dispose the brush generally parallel to the road surface.
